US00D791153S

(12) **United States Design Patent** (10) **Patent No.:** **US D791,153 S**
Rice et al. (45) **Date of Patent:** **** Jul. 4, 2017**

(54) **DISPLAY SCREEN WITH GRAPHICAL USER INTERFACE**

(71) Applicant: **Microsoft Corporation**, Redmond, WA (US)

(72) Inventors: **John Clinton Rice**, Seattle, WA (US); **Adrian Rapp Milsap**, Seattle, WA (US); **Rita Yu**, Redmond, WA (US); **Adam Sidwell**, Seattle, WA (US); **Nicholas Robinson**, Sammamish, WA (US); **Craig Maitlen**, Woodinville, WA (US); **Anthony J. Giardini**, Seattle, WA (US)

(73) Assignee: **Microsoft Corporation**, Redmond, WA (US)

(**) Term: **15 Years**

(21) Appl. No.: **29/535,287**

(22) Filed: **Aug. 5, 2015**

(51) **LOC (10) Cl.** **14-04**

(52) **U.S. Cl.**

USPC **D14/486**

CLAIM

The ornamental design for a display screen with graphical user interface, as shown and described.

DESCRIPTION

The FIGURE is a front view of a display screen with graphical user interface showing our new design.

The outermost broken lines illustrate a display screen and form no part of the claimed design. The remaining broken lines, illustrating portions of the graphical user interface, form no part of the claimed design.

1 Claim, 1 Drawing Sheet
